UNITED STATES PATENT OFFICE.

LOUIS ERIC SHERMAN, OF CLAY CENTER, KANSAS.

CALENDAR.

1,179,231.

Specification of Letters Patent. Patented Apr. 11, 1916.

Application filed April 26, 1915. Serial No. 23,940.

To all whom it may concern:

Be it known that I, LOUIS ERIC SHERMAN, a citizen of the United States, residing at Clay Center, in the county of Clay and State 5 of Kansas, have invented new and useful Improvements in Calendars, of which the following is a specification.

The invention relates to a calendar, and has for its primary object to provide an 10 article of this character wherein the strip containing the indicia indicative of the days of the respective months in a year is adapted to be wound upon one roller and unwound from another so that the indicia will be 15 clearly visible through a peep opening in the front of the casing, one of the rollers being manually rotated to change the position of the strip accordingly to the month desired to be visible.

20 Another object of the invention is the provision of a calendar which can be changed in a convenient and quick manner, the rollers being held in place within the casing in a novel manner, while the said casing is 25 unique, ornamental and attractive in appearance.

A further object of the invention is the provision of a calendar of this character which is simple in construction, thoroughly 30 reliable and efficient in its purpose, and inexpensive in manufacture.

With these and other objects in view, the invention consists in the construction, combination and arrangement of parts as will 35 be hereinafter fully described, illustrated in the accompanying drawing, and pointed out in the claim hereunto appended.

In the drawing: Figure 1 is a front elevation of a calendar constructed in accordance with the invention. Fig. 2 is an edge elevation. Fig. 3 is a vertical transverse sectional view therethrough. Fig. 4 is a horizontal transverse sectional view on the line 4-4 of Fig. 1.

45 Similar reference characters indicate corresponding parts throughout the several views in the drawing.

Referring to the drawing in detail, A designates generally the casing which is formed 50 with a back 5, sides 6, top and bottom 7 and 8, respectively, and a front hinged door 9 to provide a chamber in which are arranged parallel rollers 10 and 11, respectively, having fixed thereto the ends of a flexible strip 55 12, preferably made from fabric which is

adapted to be alternately wound and unwound on and from the rollers for a purpose presently described. The shaft 13 of each roller 10 and 11 has its ends journaled in the sides 6, one of which is formed with a 60 removable section 14 which is suitably detachably fastened in place, and when detached permits the rollers to be removed from the chamber as the occasion may require.

One of the shafts 13 is formed with a crank 15 without the casing for the convenient turning thereof, and upon the strip 12 is glued or otherwise fastened sheets 16 containing calendar months and dates, the 70 said sheets being readily moved at will to perpetuate the calendar. Fixed to the respective shafts 13 are pulleys 17, over which is trained an endless cable 18 so that the rollers will turn in unison.

75 Formed in the front door 9 is an opening 19 covered by a transparent panel 20 to make visible the calendar sheets from without the casing, while rotatably mounted in the said door is a knob 20 having an inner catch 22 to engage with a keeper block 23 mounted on the section 14 for holding the door closed, the knob being turned to release the door for the opening thereof to permit access to the interior of the chamber 80 within the casing. Suitably mounted in the back 5 is a mirror 24 for the convenience of the user, and this back is provided with a hole 25 to permit the hanging of the calendar upon the wall or other support. At one 85 side of the calendar sheets are memorandum spaces 26 which are divided from each other by the transverse lines 27 so that on the opening of the door any memoranda can be made in the space 26 for attention in a 90 given month, and this memoranda will be visible through the opening in the door when closed.

95 What is claimed is:

In a calendar, a body forming a casing 100 having an open front, a door section closing said open front and having a transparent panel for making visible the calendar, one side only of the body being cut away for a portion of its length, a section in correspondence with the cut away portion and fitted therein, a link swingingly connecting the section at its upper end to the body, said section being provided with notches, said body being provided with notches coincid- 105 110

ing with the notches in the section, winding and unwinding rolls having journal ends detachably engaged in the sides of the body, the journal ends at one side of said body being loosely received in the notches and freed therefrom on the swinging of the section out of the cut away portions, and a fastener passed through the section to hold

the same in position for closing the cut away portion.

In testimony whereof I affix my signature in presence of two witnesses.

LOUIS ERIC SHERMAN.
